UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Continuation of application Serial No. 340,566, filed November 25, 1919. This application filed December 5, 1921. Serial No. 519,857.

To all whom it may concern:

Be it known that I, CHARLES L. GOODRUM, a citizen of the United States, residing at New York, in the county of New York, 5 State of New York, have invented certain new and useful Improvements in Telephone Systems, of which the following is a full, clear, concise, and exact description.

This invention relates to telephone systems and more particularly to automatic systems of the type popularly known as full relay systems.

By means of novel circuit arrangements, I have produced a full relay system which 15 is efficient, simple of operation, rugged and of low first cost.

The invention relates to a system of the general type disclosed in Patent No. 1,107, 152 issued to E. E. Clement, August 11, 20 1914, and this application is to be considered as a continuation of my copending application, Serial No. 340,566, filed November 25, 1919.

The present invention is an improvement 25 over the invention disclosed in the aforesaid patent in that by means of novel circuit arrangements and novel mechanisms, I have been able to further reduce the number of relay magnets.

30 The object of the invention, therefore, is to provide an improved telephone system in which only relays and magnets are employed to perform the switching operations.

A feature of the invention is the provision 35 of a system of actuating and locking bars or members for controlling switching mechanisms and which are operated by common magnets under the control of the subscribers. Heretofore, mechanisms, such as 40 cross-bar switches, have been provided for establishing connections, but the present invention, while in a manner similar to the cross-bar switch, is a distinct improvement thereon. The switch of the present 45 invention on the other hand is adapted for instant operation, that is to say, the two necessary operations of connecting the calling line to a transfer circuit and of connecting the transfer circuit to an idle trunk 50 are performed simultaneously.

Another feature of this invention therefore, is the provision of means for operating the line and trunk bars simultaneously.

A further feature of the invention is a switching system wherein a plurality of 55 coexisting connections may be established at contacts controlled by a single actuating bar or switching member of a unitary switching mechanism, the switching mechanism comprising a plurality of cooperating 60 switching members each controlling a plurality of said contacts. A portion of the actuating bars or switching members may be assigned to serve incoming circuits such as lines, and other bars may serve outgoing 65 circuits such as trunks. By operating a single bar serving a plurality of incoming circuits and by operating the bars pertaining to idle outgoing circuits or trunks, one or any desired number of incoming 70 circuits may be connected to said trunks. The same is true of each of the remaining switching bars assigned to serve other incoming circuits.

Another feature of the invention is the 75 provision of circuit arrangements whereby any switching member of the unitary mechanism which serves incoming circuits may in a series of successive operations act to establish co-existing connections between 80 any desired variable number of incoming circuits and outgoing circuits. Any suitable means may be utilized for operating the switching members as, for example, electromagnets. These magnets upon being energized 85 operate the switching members which actuate the contact sets to establish the connections between incoming and outgoing circuits. Heretofore, the practice has been to have a common operating member of this 90 general character which could only be utilized for setting up a single connection at any one time, since the establishment of such a connection is an act of appropriation 95 and temporarily converts the apparatus from a common to an individual basis. In the present arrangement, however, in which the separately operable switching members are freed once a connection 100 has been established, the apparatus remains on a common basis and may be employed any desired number of times for establishing a plurality of co-existing connections.

In the drawings, Fig. 1 is a diagrammatic 105 representation of the means employed in the

present invention. Fig. 2 is a perspective view showing more in detail the organization of the trunk, actuating and locking bars and the common magnets for operating them.

There is a bar 1 individual to the trunk 2, which normally stands in the operated position. This bar has a number of ears 3 formed thereon for the purpose of moving 10 into position the dogs 4 which are pivotally supported on the bars 7 at 37. The dogs 4 are normally positioned by the springs 38 and when moved into position as shown in the lower part of Fig. 1 engage or are in a 15 position to engage the lugs 5 of switching mechanisms 8. The mechanism 8 is pivotally supported in the frame members 39 and 40 and is normally held by the spring 29 with the lug 41 on projection 9 attached 20 thereto, in engagement with stop 42 on frame member 39. When the magnet 6 is operated, the bar 7 is moved in such a manner that the dog 4 will bear against the lug 5 and rotate the switching mechanism 8 25 whereby the sets of contacts controlled thereby will be closed. After the switching mechanism 8 has been rotated the projection 9 will be moved below the level of the bar 10 so that when it is moved by means of its 30 magnet 11 the ears formed thereon such as 12 will prevent the switching mechanism 8 from moving back to its normal position.

The operation of this device will be more apparent from a detailed description of the 35 establishment of a call from a subscriber's line to the point where it is extended to a trunk.

Under normal conditions the bar 1 stands in an actuated position from the energization 40 of the magnet 13. There is a circuit for magnet 13 from ground, the upper armature and back contact of magnet 11, winding of magnet 13, to battery and ground. The movement of bar 1 as hereinbefore explained, renders all of the switching devices 45 such as 8 which are individual or are associated with the trunk 2 operable. This line of switching devices is rendered operable in that the dogs 4 associated with them are all 50 in their actuated positions so that if any one of the line bars such as 7 is actuated the corresponding switching mechanism will be rotated and only that switching mechanism in the row associated with the trunk 2 will be 55 rotated.

We will assume that the substation, herein designated 121, initiates a call. The removal of the receiver from the hook will energize line relay 14 in the usual and well 60 known manner. Relay 14 in attracting its armature places a ground on conductors 15 and 16. The ground on conductor 15 energizes the magnet 6 whereupon the switching mechanism 8 is rotated and the contacts controlled 65 thereby are all closed. The ground

on conductor 16 energizes the magnet 17 whereupon the switching mechanism 18 is rotated and the three contacts controlled thereby are closed. The line of the substation 121 is now extended from the middle 70 set of three contacts in the switching mechanism 8 over the transfer circuit 19 through the set of contacts controlled by the switching mechanism 18 to the trunk 2. In a manner well known in the art, a ground will 75 be placed on the third conductor 20 as soon as trunk 2 is seized, which will be extended through contacts of the switching mechanisms to the cutoff relay 21. Cutoff relay 21 will thereupon attract its armatures and 80 cause the deenergization of the line relay 14.

At the time that magnets 17 and 6 became energized a circuit was closed from ground, the contact and armature of magnet 17, the conductor 22, the contact and 85 armature of magnet 6, the conductor 23, the normal contact controlled by the innermost upper armature of magnet 11, the winding of magnet 11 to battery and ground. Through this circuit magnet 11 becomes 90 energized and causes the movement of the locking bar 10 whereby the switching mechanisms 8 and 18 are locked into their actuated positions. The operation of the magnet 11 being that of a power magnet is somewhat 95 slower than the operation of quick acting relays such as cutoff relay 21 and line relay 14. Therefore, as soon as the switching mechanisms 8 and 18 have been actuated through the energization of magnets 6 and 17 the ground will be removed from conductor 23 very shortly after magnet 11 has been energized whereupon the ground on conductor 23 will not be extended from the contact 24 to the next magnet 25. However, 100 the ground on conductor 20 will be connected through the contact 26 to the winding of magnet 11 to hold it energized. Through the upper armature and front contact of magnet 11 the ground for the energization 105 of magnet 13 will be transferred to the winding of magnet 27 whereby the next trunk is selected and ready for seizure by any incoming line and magnet 13 becomes 110 deenergized.

In this manner during the conversational period, there will be only one magnet and one relay, that is to say, magnet 11 and relay 21, tied to conductor 20 and held energized by the ground thereon.

The further extension of the call and the manner in which the substation 121 is extended to a called subscriber not being pertinent to an understanding of the present invention have not been disclosed herein.

Upon the termination of the conversational period ground is removed from conductor 20 in any well known manner and the magnet 11 releases whereby the bar 10 is, through the agency of the spring 28, re- 120

turned to its normal position and the switching mechanisms 8 and 18 by means of their springs such as 29 are returned to their normal positions. Such a disconnection is practically instantaneous. Through the breaking of the connection to the third wire the cutoff relay 21 is deenergized.

If during the existence of a connection established as previously described from the 10 substation 121 to the idle trunk 2, a second substation 111 in the same subgroup as substation 121 initiates a connection, line relay 34, individual to the line of substation 111, becomes energized and at its inner 15 armature contact again establishes the previously traced circuit for the line bar magnet 6, which is common to all of the lines of the subgroup to which substations 111 and 121 belong. At its outer armature contact, line relay 34 establishes a circuit for 20 magnet 35. In a manner previously described magnets 6 and 35 become energized and operate their respective bars. Since at this time magnet 27 of the bar appertaining 25 to the next idle trunk 36, is in an operated condition the switching mechanisms 32 and 33 are operated through the operation of magnets 6 and 35, respectively, and the substation 111 is thereby connected to the trunk 36. Following the establishment of the 30 connection between substation 111 and trunk 36, the magnets 6 and 35 become deenergized in the manner previously described and the connection is maintained through the operation of the locking magnet 25. In this 35 manner magnet 6 may be repeatedly operated to serve in the establishment of a plurality of coexisting connections.

What is claimed is:

40 1. In a telephone system, a group of calling lines, a group of transfer circuits, a trunk line, a switching mechanism to connect said lines to said transfer circuits, a switching mechanism individual to each 45 transfer circuit to connect said transfer circuits to said trunk line, an actuating bar for rendering said switching mechanisms operative, a magnet common to said calling lines to actuate said first switching mechanism when made operative by said actuating bar, and a magnet individual to each of 50 said lines to actuate a particular one of said individual switching mechanisms when made operative by said actuating bar.

55 2. In a telephone system, a group of calling lines, a group of transfer circuits, a trunk line, a switching mechanism to connect said lines to said transfer circuits, a switching mechanism individual to each 60 transfer circuit to connect said transfer circuits to said trunk line, an actuating bar for rendering said switching mechanisms operative, a magnet common to said calling lines to actuate said first switching mechanism when made operative by said actuating bar, and a locking bar under control of a calling line for locking 65 said actuated switching mechanisms into their actuated positions.

ing bar, a magnet individual to each of said calling lines to actuate a particular one of said individual switching mechanisms when made operative by said actuating bar, and means to operate said common magnet 70 and one of said individual magnets simultaneously.

3. In a telephone system, a group of calling lines, a group of transfer circuits, a trunk line a switching mechanism to connect said lines to said transfer circuits, a switching mechanism individual to each transfer circuit to connect said transfer circuits to said trunk line, an actuating bar for rendering said switching mechanisms 75 operative, a magnet common to said lines to actuate said first switching mechanism when made operative by said actuating bar, a magnet individual to each of said lines to actuate a particular one of said individual 80 switching mechanisms when made operative by said actuating bar, and a locking bar for locking said actuated switching mechanisms against release.

4. In a telephone system, a group of calling lines, a group of transfer circuits, a trunk line, a switching mechanism to connect said lines to said transfer circuits, a switching mechanism individual to each transfer circuit to connect said transfer circuits to said trunk line, an actuating bar for rendering said switching mechanisms 90 operative, a magnet common to said lines to actuate said first switching mechanism when made operative by said actuating bar, 95 a magnet individual to each of said switching mechanisms when made operative by said actuating bar, means to operate said common magnet and one of said individual magnets simultaneously, and a locking bar 100 for locking said actuated switching mechanisms against release.

5. In a telephone system, a group of calling lines, a group of transfer circuits, a trunk line, a switching mechanism to connect said lines to said transfer circuits, a switching mechanism individual to each transfer circuit to connect said transfer circuits to said trunk line, an actuating bar for rendering said switching mechanisms 110 operative, a magnet common to said lines to actuate said first switching mechanism when made operative by said actuating bar, a magnet individual to each of said lines to actuate a particular one of said individual 115 switching mechanisms when made operative by said actuating bar, and a locking bar under control of a calling line for locking said actuated switching mechanisms into 120 their actuated positions.

6. In a telephone system, a group of calling lines, a group of transfer circuits, a trunk line, a switching mechanism to connect said lines to said transfer circuits, a switching mechanism individual to each 125

1 transfer circuit to connect said transfer circuits to said trunk line, an actuating bar 5 for rendering said switching mechanisms operative, a magnet common to said lines to actuate said first switching mechanism when made operative by said actuating bar, a magnet individual to each of said lines to actuate a particular one of said individual switching mechanisms when made operative 10 by said actuating bar, means to operate said common magnet and one of said individual magnets simultaneously, and a locking bar under control of a calling line for locking said actuated switching mechanisms into their actuated positions.

7. In a telephone system, a plurality of groups of lines, a group of trunks, a group of transfer circuits individual to each trunk in said group, a switching mechanism individual to each of said transfer circuits, a switching mechanism individual jointly to each said group of lines and each said group of transfer circuits, a trunk bar individual to each said trunk for rendering said switching mechanisms individual to said trunk operative, means for normally holding one of said trunk bars in an operative position, means responsive to the calling condition of one of said lines for actuating said switching mechanism individual jointly to the group of lines including said calling line and said group of transfer circuits individual to said trunk whose trunk bar has been operated to connect each of said lines in the group including said calling line to a transfer circuit, means also responsive to the calling condition of said line for actuating said switching mechanism individual to that transfer circuit connected 40 to said calling line for connecting said calling line to said trunk, and means for locking said actuated switching mechanism into their actuated positions.

8. In a telephone system, a plurality of groups of lines, a group of trunks, a group of transfer circuits individual to each trunk in said group, a switching mechanism individual to each said transfer circuit, a switching mechanism individual jointly to each said group of lines and each said group of transfer circuits, a trunk bar individual to each said trunk for rendering said switching mechanisms individual to said transfer circuits of the group individual to said trunk operative, means for normally holding one of said trunk bars in an operative position, means responsive to the calling condition of one of said lines for actuating said switching mechanism individual jointly to the group of lines including said calling line and said group of transfer circuits individual to said trunk, whose trunk bar has been operated to connect each of said lines in the group including said calling line to the transfer circuit, means also

responsive to the calling condition of said line for actuating said switching mechanism individual to that transfer circuit connected to said calling line for connecting said calling line to said trunk, means for locking said actuated switching mechanisms into their actuated position, and means under control of said calling line for controlling said locking means. 70

9. In a telephone system, a plurality of groups of lines, a group of trunks, a group of transfer circuits individual to each trunk in said group, a switching mechanism individual to each said transfer circuit, a switching mechanism individual jointly to each of said group of lines and each said group of transfer circuits, a trunk bar individual to each said trunks for rendering said switching mechanisms individual to said transfer circuits of the group individual to said trunk operative, means for normally holding one of said trunk bars in an operative position, means responsive to the calling condition of one of said lines for actuating said switching mechanism individual jointly to the group of lines including said calling line and said group of transfer circuits individual to said trunk whose trunk bar has been operated to connect each of said lines in the group including said calling line to a transfer circuit, means also responsive to the calling condition of said line for actuating said switching mechanism individual to that transfer circuit connected to said calling line for connecting said calling line to said trunk, means for locking said actuated switching mechanisms into their actuated positions, and means responsive to the actuation of said locking means for releasing said trunk bar. 95 100 105

10. In a telephone system, a plurality of groups of lines, a group of trunks, a group of transfer circuits individual to each trunk in said group, a switching mechanism individual to each said transfer circuit, a switching mechanism individual jointly to each said group of lines and each said group of transfer circuits, a trunk bar individual to each said trunk for rendering said switching mechanisms individual to said transfer circuits of the group individual to said trunk operative, means for normally holding one of said trunk bars in an operative position, means responsive to the calling condition of one of said lines for actuating said switching mechanism individual jointly to the group of lines including said calling line and said group of transfer circuits individual to said trunk whose trunk bar has been operated, to connect each of said lines in the group including said calling line to a transfer circuit, means also responsive to the calling condition of said line for actuating said switching mechanism individual to that transfer circuit connected to said calling line 110 115 120 125 130

for connecting said calling line to said trunk, means for locking said actuated switching mechanisms into their actuated positions, means responsive to the actuation of said locking means for releasing said trunk bar, and means for thereupon actuating the trunk bar of the next idle trunk.

11. In a telephone system, incoming lines, transfer circuits, an outgoing line, switching mechanisms to connect said outgoing line to said incoming lines through said transfer circuits, an actuating bar for rendering said switching mechanisms operative, and a magnet individual to each of said switching mechanisms to actuate said switching mechanisms when made operative by said actuating bar.

12. In a telephone system, incoming lines, groups of transfer circuits, outgoing lines, switching mechanisms, incoming line magnets, outgoing line magnets corresponding in number to the number of transfer circuits in a group, and bars individual to each said group of transfer circuits cooperating with said magnets to actuate said mechanisms to extend said incoming lines through said transfer circuits to said outgoing lines.

13. In a telephone system, incoming lines, groups of transfer circuits, outgoing lines, separately movable switching mechanisms, incoming line magnets, outgoing line magnets corresponding in number to the number of transfer circuits in a group, and bars cooperating with said magnets to actuate a plurality of said switching mechanisms to extend said incoming lines through said transfer circuits to said outgoing lines.

14. In a telephone system, incoming lines, transfer circuits, outgoing lines, separately movable switching mechanisms for connecting said incoming lines to said transfer circuits, separately movable switching mechanisms for connecting said transfer circuits to said outgoing lines, magnets for said switching mechanisms, and bars for cooperating with said magnets to actuate a plurality of said switching mechanisms whereby said incoming lines may be extended through said transfer circuits to said outgoing lines.

15. In a telephone system, incoming lines, transfer circuits, outgoing lines, separately movable switching mechanisms for connecting said incoming lines to said transfer circuits, separately movable switching mechanisms for connecting said transfer circuits to said outgoing lines, magnets for said switching mechanisms, and bars cooperating with said magnets to simultaneously actuate a plurality of said switching mechanisms whereby said incoming lines may be extended through said transfer circuits to said outgoing lines.

16. In a telephone system, incoming lines, transfer circuits, outgoing lines, separately movable switching mechanisms for connect-

ing said incoming lines to said transfer circuits, separately movable switching mechanisms for connecting said transfer circuits to said outgoing lines, magnets for said switching mechanisms, and bars cooperating with said magnets to selectively actuate a plurality of said switching mechanisms whereby said incoming lines may be extended through said transfer circuits to said outgoing lines.

17. In a telephone system, incoming lines, transfer circuits, outgoing lines, separately operable switching mechanisms for connecting said incoming lines to said transfer circuits, separately operable switching mechanisms for connecting said transfer circuits to said outgoing lines, incoming line magnets each having control over a plurality of said first mentioned switching mechanisms, outgoing line magnets each having control over a plurality of said latter switching mechanisms, bars cooperating with said magnets whereby a single one of said mechanisms controlled by each of said magnets may be actuated in conjunction with such of said magnets as are actuated, and means to connect an incoming line through a transfer circuit to an outgoing line.

18. In a telephone system, incoming lines, transfer circuits, outgoing lines, separately operable switching mechanisms for connecting said incoming lines through said transfer circuits to said outgoing lines, incoming line magnets, outgoing line magnets, actuating bars operated by said magnets, magnets for rendering said bars effective to actuate switching mechanisms, and means for simultaneously operating an incoming line magnet and an outgoing line magnet to actuate said switching mechanisms to connect the incoming line through a transfer circuit to an outgoing line.

19. In a telephone system, incoming lines, groups of transfer circuits, outgoing lines, separately movable switching mechanisms, incoming line magnets, outgoing line magnets corresponding in number to the number of transfer circuits in a group, and bars cooperating with said magnets to actuate a plurality of said switching mechanisms to extend coexisting connections from said incoming lines through said transfer circuits to said outgoing lines.

20. In a telephone system, incoming lines, transfer circuits, outgoing lines, separately movable switching mechanisms for connecting said incoming lines to said transfer circuits, separately movable switching mechanisms individual to each of said transfer circuits for connecting them to said outgoing lines, magnets for said switching mechanisms, and bars for cooperating with said magnets to actuate a plurality of said switching mechanisms whereby coexisting

- connections may be extended from said incoming lines through said transfer circuits to said outgoing lines.
21. In a telephone system, incoming lines, transfer circuits, outgoing lines, separately movable switching mechanisms for connecting said incoming lines to said transfer circuits, separately movable switching mechanisms individual to each of said transfer circuits for connecting them to said outgoing lines, magnets for said switching mechanisms, and bars cooperating with said magnets to simultaneously actuate a plurality of said switching mechanisms whereby coexisting connections may be extended from said incoming lines through said transfer circuits to said outgoing lines.
22. In a telephone system, incoming lines, transfer circuits, outgoing lines, separately movable switching mechanisms for connecting said incoming lines to said transfer circuits, separately movable switching mechanisms individual to each of said transfer circuits for connecting them to said outgoing lines, magnets for said switching mechanisms, and bars cooperating with said magnets to selectively actuate a plurality of said switching mechanisms whereby coexisting connections may be extended from said incoming lines through said transfer circuits to said outgoing lines.
23. In a telephone system, incoming lines, transfer circuits, an outgoing line having multiple contacts corresponding to said transfer circuits, separately movable switching mechanisms, incoming line magnets, an outgoing line magnet, a single operating magnet for each of said transfer circuits, and means to operate an incoming line magnet, a transfer circuit magnet and an outgoing line magnet to actuate a plurality of said switching mechanisms to extend an incoming line through a transfer circuit to said outgoing line.
24. In a telephone system, incoming lines, groups of transfer circuits, outgoing lines, separately movable switching mechanisms, incoming line magnets, outgoing line magnets corresponding in number to the number of transfer circuits in a group, and bars cooperating with said magnets to actuate a plurality of said switching mechanisms to extend said incoming lines through one of said groups of transfer circuits to one of said outgoing lines.
25. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, magnets for said switching mechanisms and bars for cooperating with said magnets to actuate a plurality of said switching mechanisms whereby said incoming lines may be extended through said transfer circuits to said outgoing lines.
26. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, and a plurality of bars for controlling and operating said switching mechanisms, certain of said bars maintaining said switching mechanisms in operation independently of mechanical connection to said other bars which assisted in the operation of said mechanisms.
27. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, bars for preparing said switching mechanisms for operation, other bars cooperating mechanically with said first bars for causing and maintaining the operation of said prepared switching mechanisms, and means for returning said first bars to a normal position independent of any mechanical connection with said operated switching mechanisms.
28. In a telephone system, incoming lines, transfer circuits, outgoing lines having multiple contacts corresponding to said transfer circuits, separately movable switching mechanisms, incoming line bars, outgoing line bars, and bars cooperating with said line bars to actuate and maintain actuated said switching mechanisms to extend said incoming lines through said transfer circuits to said outgoing lines, said switching mechanisms being maintained in operated condition independently of said line bars.
29. In a telephone system, incoming lines, transfer circuits, outgoing lines having multiple contacts corresponding to said transfer circuits, separately movable switching mechanisms, incoming line bars, outgoing line bars, and bars cooperating with said line bars to actuate and maintain in actuated condition said switching mechanisms to extend said incoming lines through said transfer circuits to said outgoing lines, said switching mechanisms being maintained in operated condition independently of any mechanical connection with said line bars.
30. In a telephone system, incoming lines, transfer circuits, outgoing lines having multiple contacts corresponding to said transfer circuits, separately movable switching mechanisms to connect said incoming lines to said transfer circuits, separately movable switching mechanisms to connect said transfer circuits to said outgoing lines,

incoming line magnets, outgoing line magnets, bars cooperating with said magnets to actuate a plurality of said mechanisms and a circuit for controlling said bars controlled by said incoming line magnets and said outgoing line magnets.

31. In a telephone system, incoming lines, transfer circuits, outgoing lines having multiple contacts corresponding to said transfer circuits, separately movable switching mechanisms to connect said incoming lines to said transfer circuits, separately movable switching mechanisms to connect said transfer circuits to said outgoing lines, incoming line magnets, outgoing line magnets, bars cooperating with said magnets to actuate a plurality of said mechanisms and a circuit for controlling said bars jointly controlled by said incoming line magnets and said outgoing line magnets.

32. In a telephone system, incoming lines, transfer circuits, an outgoing line having multiple contacts corresponding to said transfer circuits, separately movable switching mechanisms, incoming line magnets, outgoing line magnets, transfer circuit magnets, bars controlled by said magnets for actuating said switching mechanisms to extend said incoming lines through said transfer circuits to said outgoing line and a circuit for said transfer circuit magnets controlled by said incoming line magnets and said outgoing line magnets.

33. In a telephone system, incoming lines, transfer circuits, an outgoing line having multiple contacts corresponding to said transfer circuits, separately movable switching mechanisms, incoming line magnets, outgoing line magnets, transfer circuit magnets, bars controlled by said magnets for actuating said switching mechanisms to ex-

tend said incoming lines through said transfer circuits to said outgoing line and a circuit for said transfer circuit magnets jointly controlled by said incoming line magnets 45 and said outgoing line magnets.

34. In a telephone system, incoming lines, transfer circuits, an outgoing line having multiple contacts corresponding to said transfer circuits, said outgoing line comprising a pair of talking conductors and a release trunk, separately movable switching mechanisms, incoming line magnets, outgoing line magnets, transfer circuit magnets, bars controlled by said magnets for actuating said switching mechanisms to extend an incoming line through one of said transfer circuits to said outgoing line, a circuit for said transfer circuit magnets controlled by said incoming line magnets and said outgoing line magnets and means for shifting the control of said transfer circuit magnets from said line magnets to said release trunk.

35. In a telephone system, groups of incoming lines, groups of transfer circuits, outgoing lines each having multiple contacts corresponding to the number of transfer circuits in a group, incoming line magnets, transfer circuit magnets, outgoing line magnets and bars under control of said 70 magnets to extend said incoming lines through said transfer circuits to said outgoing lines, and a circuit interlinking said transfer circuit magnets with means controlled by said magnets incident to the operation of one of said magnets for preparing for operation the next in order idle one of said magnets.

In witness whereof, I hereunto subscribe my name this 2nd day of December, A. D. 30 1921.

CHARLES L. GOODRUM.

DISCLAIMER.

1,484,771.—*Charles L. Goodrum*, New York, N. Y. TELEPHONE SYSTEM. Patent dated February 28, 1924. Disclaimer filed January 5, 1926, by the patentee, the assignee, *Western Electric Company, Incorporated*, consenting.

Hereby enters this disclaimer to the said claims of said Letters Patent which are in the following words, to wit:

“ 11. In a telephone system, incoming lines, transfer circuits, an outgoing line, switching mechanisms to connect said outgoing line to said incoming lines through said transfer circuits, an actuating bar for rendering said switching mechanisms operative, and a magnet individual to each of said switching mechanisms to actuate said switching mechanisms when made operative by said actuating bar.

“ 14. In a telephone system, incoming lines, transfer circuits, outgoing lines, separately movable switching mechanisms for connecting said incoming lines to said transfer circuits, separately movable switching mechanisms for connecting said transfer circuits to said outgoing lines, magnets for said switching mechanisms, and bars for cooperating with said magnets to actuate a plurality of said switching mechanisms whereby said incoming lines may be extended through said transfer circuits to said outgoing lines.

“ 15. In a telephone system, incoming lines, transfer circuits, outgoing lines, separately movable switching mechanisms for connecting said incoming lines to said transfer circuits, separately movable switching mechanisms for connecting said transfer circuits to said outgoing lines, magnets for said switching mechanisms, and bars cooperating with said magnets to simultaneously actuate a plurality of said switching mechanisms whereby said incoming lines may be extended through said transfer circuits to said outgoing lines.

“ 16. In a telephone system, incoming lines, transfer circuits, outgoing lines, separately movable switching mechanisms for connecting said incoming lines to said transfer circuits, separately movable switching mechanisms for connecting said transfer circuits to said outgoing lines, magnets for said switching mechanisms, and bars cooperating with said magnets to selectively actuate a plurality of said switching mechanisms whereby said incoming lines may be extended through said transfer circuits to said outgoing lines.

“ 17. In a telephone system, incoming lines, transfer circuits, outgoing lines, separately operable switching mechanisms for connecting said incoming lines to said transfer circuits, separately operable switching mechanisms for connecting said transfer circuits to said outgoing lines, incoming line magnets each having control over a plurality of said first mentioned switching mechanisms, outgoing line magnets each having control over a plurality of said latter switching mechanisms, bars cooperating with said magnets whereby a single one of said mechanisms controlled by each of said magnets may be actuated in conjunction with such of said magnets as are actuated, and means for simultaneously operating an incoming line magnet and an outgoing line magnet to connect an incoming line through a transfer circuit to an outgoing line.

“ 18. In a telephone system, incoming lines, transfer circuits, outgoing lines, separately operable switching mechanisms for connecting said incoming lines through said transfer circuits to said outgoing lines, incoming line magnets, outgoing line magnets, actuating bars operated by said magnets, magnets for rendering said bars effective to actuate switching mechanisms, and means for simultaneously operating an incoming line magnet and an outgoing line magnet to actuate said switching mechanisms to connect the incoming line through a transfer circuit to an outgoing line.

“ 20. In a telephone system, incoming lines, transfer circuits, outgoing lines, separately movable switching mechanisms for connecting said incoming lines to said transfer circuits, separately movable switching mechanisms individual to each of said transfer circuits for connecting them to said outgoing lines, magnets for said switching mechanisms, and bars for cooperating with said magnets to actuate a plurality of said switching mechanisms whereby coexisting connections may be extended from said incoming lines through said transfer circuits to said outgoing lines.

"21. In a telephone system, incoming lines, transfer circuits, outgoing lines, separately movable switching mechanisms for connecting said incoming lines to said transfer circuits, separately movable switching mechanisms individual to each of said transfer circuits for connecting them to said outgoing lines, magnets for said switching mechanisms, and bars cooperating with said magnets to simultaneously actuate a plurality of said switching mechanisms whereby coexisting connections may be extended from said incoming lines through said transfer circuits to said outgoing lines.

"22. In a telephone system, incoming lines, transfer circuits, outgoing lines, separately movable switching mechanisms for connecting said incoming lines to said transfer circuits, separately movable switching mechanisms individual to each of said transfer circuits for connecting them to said outgoing lines, magnets for said switching mechanisms, and bars cooperating with said magnets to selectively actuate a plurality of said switching mechanisms whereby coexisting connections may be extended from said incoming lines through said transfer circuits to said outgoing lines.

"23. In a telephone system, incoming lines, transfer circuits, an outgoing line having multiple contacts corresponding to said transfer circuits, separately movable switching mechanisms, incoming line magnets, an outgoing line magnet, a single operating magnet for each of said transfer circuits, and means to operate an incoming line magnet, a transfer circuit magnet and an outgoing line magnet to actuate a plurality of said switching mechanisms to extend an incoming line through a transfer circuit to said outgoing line.

"25. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, magnets for said switching mechanisms and bars for cooperating with said magnets to actuate a plurality of said switching mechanisms whereby said incoming lines may be extended through said transfer circuits to said outgoing lines.

"26. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, and a plurality of bars for controlling and operating said switching mechanisms, certain of said bars maintaining said switching mechanisms in operation independently of mechanical connection to said other bars which assisted in the operation of said mechanisms.

"27. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, bars for preparing said switching mechanisms for operation, other bars cooperating mechanically with said first bars for causing and maintaining the operation of said prepared switching mechanisms, and means for returning said first bars to a normal position independent of any mechanical connection with said operated switching mechanisms.

"28. In a telephone system, incoming lines, transfer circuits, outgoing lines having multiple contacts corresponding to said transfer circuits, separately movable switching mechanisms, incoming line bars, outgoing line bars, and bars cooperating with said line bars to actuate and maintain actuated said switching mechanisms to extend said incoming lines through said transfer circuits to said outgoing lines, said switching mechanisms being maintained in operated condition independently of said line bars.

"29. In a telephone system, incoming lines, transfer circuits, outgoing lines having multiple contacts corresponding to said transfer circuits, separately movable switching mechanisms, incoming line bars, outgoing line bars, and bars cooperating with said line bars to actuate and maintain in actuated condition said switching mechanisms to extend said incoming lines through said transfer circuits to said outgoing lines, said switching mechanisms being maintained in operated condition independently of any mechanical connection with said line bars."

[Official Gazette January 26, 1926.]

DISCLAIMER.

1,484,771.—*Charles L. Goodrum*, New York, N. Y. TELEPHONE SYSTEM. Patent dated February 26, 1924. Disclaimer filed April 4, 1928, by the assignee, *Western Electric Company, Incorporated*.

Hereby enters this disclaimer to that part of the claims in said specification which are in the following words to wit:

“11. In a telephone system, incoming lines, transfer circuits, an outgoing line, switching mechanisms to connect said outgoing line to said incoming lines through said transfer circuits, an actuating bar for rendering said switching mechanisms operative, and a magnet individual to each of said switching mechanisms to actuate said switching mechanisms when made operative by said actuating bar.”

“14. In a telephone system, incoming lines, transfer circuits, outgoing lines, separately movable switching mechanisms for connecting said incoming lines to said transfer circuits, separately movable switching mechanisms for connecting said transfer circuits to said outgoing lines, magnets for said switching mechanisms, and bars for cooperating with said magnets to actuate a plurality of said switching mechanisms whereby said incoming lines may be extended through said transfer circuits to said outgoing lines.

“15. In a telephone system, incoming lines, transfer circuits, outgoing lines, separately movable switching mechanisms for connecting said incoming lines to said transfer circuits, separately movable switching mechanisms for connecting said transfer circuits to said outgoing lines, magnets for said switching mechanisms, and bars cooperating with said magnets to simultaneously actuate a plurality of said switching mechanisms whereby said incoming lines may be extended through said transfer circuits to said outgoing lines.

“16. In a telephone system, incoming lines, transfer circuits, outgoing lines, separately movable switching mechanisms for connecting said incoming lines to said transfer circuits, separately movable switching mechanism for connecting said transfer circuits to said outgoing lines, magnets for said switching mechanisms, and bars cooperating with said magnets to selectively actuate a plurality of said switching mechanisms whereby said incoming lines may be extended through said transfer circuits to said outgoing lines.

“17. In a telephone system, incoming lines, transfer circuits, outgoing lines, separately operable switching mechanisms for connecting said incoming lines to said transfer circuits, separately operable switching mechanisms for connecting said transfer circuits to said outgoing lines, incoming line magnets each having control over a plurality of said first mentioned switching mechanisms, outgoing line magnets each having control over a plurality of said latter switching mechanisms, bars cooperating with said magnets whereby a single one of said mechanisms controlled by each of said magnets may be actuated in conjunction with such of said magnets as are actuated, and means for simultaneously operating an incoming line magnet and an outgoing line magnet to connect an incoming line through a transfer circuit to an outgoing line.

“18. In a telephone system, incoming lines, transfer circuits, outgoing lines, separately operable switching mechanisms for connecting said incoming lines through said transfer circuits to said outgoing lines, incoming line magnets, outgoing line magnets, actuating bars operated by said magnets, magnets for rendering said bars effective to actuate switching mechanisms, and means for simultaneously operating an incoming line magnet and an outgoing line magnet to actuate said switching mechanisms to connect the incoming line through a transfer circuit to an outgoing line.”

“20. In a telephone system, incoming lines, transfer circuits, outgoing lines, separately movable switching mechanisms for connecting said incoming lines to said transfer circuits, separately movable switching mechanisms individual to each of said transfer circuits for connecting them to said outgoing lines, magnets for said switching mechanisms, and bars for cooperating with said magnets to actuate a plurality of said switching mechanisms whereby coexisting connections may be extended from said incoming lines through said transfer circuits to said outgoing lines.

“21. In a telephone system, incoming lines, transfer circuits, outgoing lines, separately movable switching mechanisms for connecting said incoming lines to said transfer circuits, separately movable switching mechanisms individual to each of

said transfer circuits for connecting them to said outgoing lines, magnets for said switching mechanisms, and bars cooperating with said magnets to simultaneously actuate a plurality of said switching mechanisms whereby coexisting connections may be extended from said incoming lines through said transfer circuits to said outgoing lines.

"22. In a telephone system, incoming lines, transfer circuits, outgoing lines, separately movable switching mechanisms for connecting said incoming lines to said transfer circuits, separately movable switching mechanisms individual to each of said transfer circuits for connecting them to said outgoing lines, magnets for said switching mechanisms, and bars cooperating with said magnets to selectively actuate a plurality of said switching mechanisms whereby coexisting connections may be extended from said incoming lines through said transfer circuits to said outgoing lines.

"23. In a telephone system, incoming lines, transfer circuits, an outgoing line having multiple contacts corresponding to said transfer circuits, separately movable switching mechanisms, incoming line magnets, an outgoing line magnet, a single operating magnet for each of said transfer circuits, and means to operate an incoming line magnet, a transfer circuit magnet and an outgoing line magnet to actuate a plurality of said switching mechanisms to extend an incoming line through a transfer circuit to said outgoing line."

"25. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, magnets for said switching mechanisms and bars for cooperating with said magnets to actuate a plurality of said switching mechanisms whereby said incoming lines may be extended through said transfer circuits to said outgoing lines.

"26. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, and a plurality of bars for controlling and operating said switching mechanisms, certain of said bars maintaining said switching mechanisms in operation independently of mechanical connection to said other bars which assisted in the operation of said mechanisms.

"27. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, bars for preparing said switching mechanisms for operation, other bars cooperating mechanically with said first bars for causing and maintaining the operation of said prepared switching mechanisms, and means for returning said first bars to a normal position independent of any mechanical connection with said operated switching mechanisms.

"28. In a telephone system, incoming lines, transfer circuits, outgoing lines having multiple contacts corresponding to said transfer circuits, separately movable switching mechanisms, incoming line bars, outgoing line bars, and bars cooperating with said line bars to actuate and maintain actuated said switching mechanisms to extend said incoming lines through said transfer circuits to said outgoing lines, said switching mechanisms being maintained in operated condition independently of said line bars.

"29. In a telephone system, incoming lines, transfer circuits, outgoing lines having multiple contacts corresponding to said transfer circuits, separately movable switching mechanisms, incoming line bars, outgoing line bars, and bars cooperating with said line bars to actuate and maintain in actuated condition said switching mechanisms to extend said incoming lines through said transfer circuits to said outgoing lines, said switching mechanisms being maintained in operated condition independently of any mechanical connection with said line bars."
